THOMAS APPLETON, OF LAKE VILLAGE, NEW HAMPSHIRE.

Design No. 4,389, dated October 11, 1870.

DESIGN FOR A STOCKING.

The Schedule referred to in these Letters Patent and making part of the same.

To all persons to whom these presents may come:

Be it known that I, THOMAS APPLETON, of Lake Village, of the county of Belknap and State of New Hampshire, have invented or produced a new, useful, and ornamental Design for a Stocking or Hose; and do hereby declare the same to be fully represented in the accompanying drawing, and to be thus described:

Figure 1 of such drawing denotes a side view of the stocking, and the two forms of stitches or knitting used in the production of my design.

Figure 2 is a representation, on an enlarged scale, of the plain and tuck stitching.

In carrying out my design, I make the stocking, from the calf of the leg downward, including the ankle and foot portions of "plain stitching" or knitting, as performed by what is termed a "circular-stocking loom," with a continuous thread or yarn; and I also make all from the base of the calf up to the mouth or top of the stocking, of what is termed "tuck-stitching," as made by the circular knitting-machine or stocking-loom, with the continuous thread or yarn. These kinds of knitting are soon understood by persons engaged in the trade, or in the manufacture of stockings or fabrics of like nature.

In fig. 1 of the drawing—

A denotes the part or parts formed of the "plain stitch," and

B, the portion of the leg formed of the "tuck-stitch," the line *a a* representing the junction of the two kinds of knitting.

In fig. 2 the "plain stitching" is shown at *b*, and the "tuck stitching" at *c*, the two being accomplished by a continuous thread, the interlooping of the loops of which is exhibited in said fig. 2.

The object of so making a stocking is to obtain a smaller ankle and a wider calf for a stocking knit or formed in a circular knitting-loom; also to render it easier to "board" the stocking.

By this mode of making a stocking, the disadvantage of being the same width at ankle, calf and top is removed from the "circular stockings," as heretofore made in the circular power knitting-looms used for producing such.

I am aware that it is not new to make the whole leg of a stocking and the instep part of the foot of what is termed a "rib-stitch" knitting. Also, that it is not new to make a sock with rib-stitch at the upper part of the leg portion, and therefore I make no claim to such.

A stocking made in accordance with my invention, after being boarded, will retain its proper shape, and will fit to the leg with great comfort to the wearer, as its tension on the leg is nearly if not entirely uniform from the ankle up.

What I claim as my invention or production, is—

The design, represented and described, for a stocking.

THOS. APPLETON.
